UNITED STATES PATENT OFFICE

2,408,071

ADJUSTABLE HINGE

Clarence M. Jahn, Chicago, Ill., assignor to Fire-
craft Corporation, a corporation of Illinois

Application August 9, 1943, Serial No. 497,884

6 Claims. (Cl. 16—129)

1

This invention relates to adjustable hinges, more particularly those for supporting doors of substantial weight.

The invention is particularly adapted, but is not limited, to the adjustable support of sound-proof doors employed in buildings tending to settle, or subject to considerable vibration, such as those in which aircraft engines and other parts are tested, and where machinery is operated. As a result of uneven settling of the building, vibration and other causes, the door frames of such buildings sometimes become warped, so that for one reason or another there occurs a displacement of the doors relative to the frames, with a resultant drop in efficiency of the sound-proofing between the door and the frame. The invention also has to do with refrigerator and other doors. Sometimes, due to improper preparation of the parts to be installed, manufacturing tolerances, etc., if no flexibility of installation of the door were possible, the door would be mounted in improper or inefficient sealing relation to the frame.

It is accordingly an object of my invention to provide a hinge support for a door enabling adjustments to be made at the time of installation and thereafter from time to time in various directions to establish and to reestablish any desired relation between the door and the associated frame.

Additional objects are to provide an adjustable hinge construction which is extremely simple, embodying a minimum of parts which may be produced inexpensively and readily assembled and disassembled, and is readily accessible for adjustment at all times.

Another object is to provide a universally adjustable door hinge construction.

A further object is to provide a door hinge construction enabling the door to be adjusted in a direction transverse to the hinge axis.

Further objects and advantages of the invention will appear as the description proceeds.

The invention will be better understood upon reference to the following description and the accompanying drawings, in which:

Fig. 1 is a fragmentary elevation of a door mounted in accordance with my invention;

Fig. 2 is a fragmentary elevation showing the hinge mounting in detail;

Figs. 3 and 4 are fragmentary sectional views taken as indicated by the lines 3—3 and 4—4, respectively, in Fig. 2;

Fig. 5 is a fragmentary perspective view of the hinge mounting;

10

2

Fig. 6 is similar to Fig. 4 but is less broken away and also shows how a door mounted on the hinge construction cooperates with a door frame; and

Fig. 7 is a fragmentary sectional view of a modified form of hinge strap eye and bearing therefor.

While there is shown and described herein certain specific structure embodying the invention, it will be manifest to those skilled in the art that various modifications and rearrangements of the parts may be made without departing from the scope of the invention, and that the same is not limited to the particular forms herein disclosed.

Referring now more particularly to the drawings, there is shown at 20 a wall such as, for example, a concrete wall having a door frame 22 at a side of which are hinge bracket supporting plates 24 adjacent the upper and lower ends 28 of the hinge stile 30 of the frame. If desired, the hinge brackets may be bolted directly to the wall or to the frame itself. The frame 22 is adapted to receive a door 32 supported by means of upper and lower hinge straps 34. These straps are bolted as at 38 or otherwise suitably secured to the door 32 and connected to a pintle bracket 40 as will appear. The number of straps may be varied as desired.

The pintle bracket 40 is preferably bolted or otherwise secured as at 42 to the respective supporting plate 24 or to the wall or frame, as the case may be. Said bracket is preferably in the form of a casting and has upper and lower arms 44 with substantially registering holes 46 therethrough. Above the upper hole 46 and below the lower hole 46 is a cavity 48 having a back wall 50 and two side walls 52 and open at the front and at the top and bottom, respectively. The ceiling 54 of the lower arm and the floor 56 of the upper arm are serrated as shown at 57 substantially from one to the other of the side walls or lugs 52.

For each cavity 48 there is provided an adjusting block 58 having a bore 60 substantially smaller than the openings 46 in the pintle bracket arms 44 and adapted to slidably fit the shank 62 of a pintle bolt 64 and having in one face thereof serrations 66 adapted to interfit with the serrations 57 of the pintle bracket 40. The length and width of the adjusting block 58 are both substantially less than the length and width, respectively, of the ceiling 54 and the floor 56, and the adjusting block accordingly may be adjusted toward and away from the back wall 50 of each opening 48 and toward and away from

the respective side walls 52 of the bracket, within the limits determined by the wall of each opening 46, cooperating with the shank 62 of the pintle bolt 64. The walls 52 of each opening 48 are tapped at 70 and receive set screws 72 adapted to clampingly engage opposite edge faces 74 of the adjusting block 58 to securely maintain the same in the desired position of adjustment. The set screws may be of the socket head or any other suitable type. Although I have shown two set 10 screws in each wall 52, placed so as to be effective irrespective of the adjustment of the adjusting block, obviously one or any other suitable number of set screws, suitably spaced, could be provided in each wall 52. The screws will positively 15 prevent shifting of the block parallel to the grooves or serrations, and, with the nut 76, will prevent the blocks from movement away from the serrated surfaces 56 so that, once the device is set up, it is impossible for the pintle bolt to shift 20 accidentally relative to the pintle bracket.

Each hinge strap 34 has an eye 80 through which the shank 62 of the pintle bolt 64 passes, between the arms 44 of the pintle bracket. The overall height of the eye is substantially less than the distance between the arms 44, and accordingly suitable spacing means is placed about 25 the shank and between the eye and the arms 44. The eye may be formed in any suitable manner. In the form of the invention shown in Figs. 1 to 6, the eye may be formed by curling the hinge strap 34 and rests on an end thrust bearing 82 under which are disposed two or any other suitable number of shims or washers 84. Four or 30 any other suitable number of additional washers 84 are disposed between the top of the eye and the upper arm 44.

I have already explained how each adjusting block may be adjusted in two directions at right angles to each other, both normal to the axis of the holes 46 in the arms 44. It is possible for either block 58 to be adjusted differently from the other block 58, due to the tolerances between the blocks and the bolt and between the washers 84 and the bolt, so that the bolt may be secured with its axis inclined to the axis of the holes 46. It is also possible to adjust the eye 80 upward or downward. Thus, to adjust the eye downward, the nut 76 is removed, the bolt 64 is raised until the free end thereof is sufficiently high to enable one of the lower washers 84 to be shifted to the upper group of washers 84, and the bolt is reinserted and secured by the nut 76. To adjust the eye upward, this same procedure is followed except that one of the upper washers is shifted to the lower group of washers. The eye 80 can thereby be adjusted in a direction parallel to the bolt.

Thus it is apparent that with my novel adjustable hinge construction it is possible to adjust the pintle bolts toward or away from the wall, toward or away from the door frame and up or down.

Instead of forming the eye by curling an end of the strap 34, I may cast the strap as shown at 99 and form the same with an eye 92 countersunk at 94 to receive combined end and radial thrust bearings 96 which preferably project slightly above and below the eye for unhampered engagement with adjacent adjusting washers.

It will be observed that in one form of door installation to which the invention is adapted, there may be provided in the door frame a continuous gasket 100 adapted to engage an inner corner portion 102 of the door, and an outer 75

portion of the door may be provided with a similar continuous gasket 104 adapted similarly to cooperate with a continuous corner portion 106 of the door frame. As has been indicated above, 5 there may be such a relative displacement of the door and frame as to materially reduce the efficiency of the sound-proofing or heat insulating contact at the gaskets, but in such event suitable adjustment may be made by the hinge construction described above and shown on the drawings to reestablish the proper relation between the door and the frame.

Various modifications may suggest themselves to those skilled in the art without departing from the spirit of my invention, and, hence, I do not wish to be restricted to the specific form shown or uses mentioned, except to the extent indicated in the appended claims.

I claim:

1. In an adjustable hinge, a pintle support comprising arms having substantially aligned holes for receiving a pintle, means for securing said arms to a wall, said arms being spaced apart to accommodate between them the eye of a door hinge strap, said holes being oversize to permit a pintle therein to be adjusted laterally relative to its axis, each arm having corrugations about its hole at the surface thereof remote from said space, the corrugations at each surface being parallel to those at the other surface, lugs adjacent the ends of the corrugations and projecting away from said space, set screws in said lugs, and adjusting blocks having pintle-receiving holes substantially smaller than the arm holes and having corrugated surfaces engageable with the corrugated surfaces of the respective arms, each block being shorter, in the direction of the corrugations, than the space between the associated lugs, said blocks being 30 shiftable free of said arms and transversely to said corrugations and reengageable with said arms at locations removed from the previous locations, with corrugated portions of said blocks and arms again mutually engaged, opposite portions of each block, in all adjustments thereof, being engageable by the associated screws so that each block may be held in the desired adjustment relative to the associated arm.

2. In an adjustable hinge, a pintle support comprising arms having substantially aligned holes for receiving a pintle, means for securing said arms to a wall, said arms being spaced apart to accommodate between them the eye of a door hinge strap, said holes being oversize to permit a pintle therein to be adjusted laterally relative to its axis, each arm having corrugations about its hole at the surface thereof remote from said space, the corrugations at each surface being parallel to those at the other surface, lugs adjacent the ends of the corrugations and projecting away from said space, set screws in said lugs, and adjusting blocks having pintle-receiving holes substantially smaller than the arm holes and having corrugated surfaces engageable with the corrugated surfaces of the respective arms, each block being shorter, in the direction of the corrugations, than the space between the associated lugs, said blocks being shiftable free of said arms and transversely to said corrugations and reengageable with said arms at locations removed from the previous locations, with corrugated portions of said blocks and arms again mutually engaged, opposite portions of each block, in all adjustments thereof, being engageable by the associated screws so that each

block may be held in the desired adjustment relative to the associated arm, each block being exposed beyond said lugs for all positions of said block to enable said block to be grasped between the thumb and a finger to facilitate installation, adjustment and removal of each block.

3. In an adjustable hinge, a pintle support comprising arms having substantially aligned holes for receiving a pintle, means for securing said arms to a wall, said arms being spaced apart to accommodate between them the eye of a door hinge strap, said holes being oversize to permit a pintle therein to be adjusted laterally relative to its axis, each arm having corrugations about its hole at the surface thereof remote from said space, the corrugations at each surface being parallel to those at the other surface, lugs adjacent the ends of the corrugations and projecting away from said space, set screws in said lugs, and adjusting blocks having pintle-receiving holes substantially smaller than the arm holes and having corrugated surfaces engageable with the corrugated surfaces of the respective arms, each block being shorter, in the direction of the corrugations, than the space between the associated lugs, said blocks being shiftable free of said arms and transversely to said corrugations and reengageable with said arms at locations removed from the previous locations, with the corrugated portions of said blocks and arms again mutually engaged, opposite portions of each block, in all adjustments thereof, being engageable by the associated screws so that each block may be held in the desired adjustment relative to the associated arm, each block being exposed beyond said lugs for all positions of said block to enable said block to be grasped between the thumb and a finger to facilitate installation, adjustment and removal of each block, and a wall-engaging portion extending from each arm away from said space and united with said lugs for reinforcing said arm.

4. In an adjustable hinge, a pintle support comprising arms having substantially aligned holes for receiving a pintle, means for securing said arms to a wall, said arms being spaced apart to accommodate between them the eye of a door hinge strap, said holes being oversize to permit a pintle therein to be adjusted laterally relative to its axis, each arm having corrugations about its hole at the surface thereof remote from said space, set screws carried in association with said arms, and adjusting blocks having pintle-receiving holes substantially smaller than the arm holes and having corrugated surfaces engageable with the corrugated surfaces of the respective arms, said blocks being shiftable free of said arms and transversely to said corrugations and reengageable with said arms at locations removed from the previous locations, with the corrugated portions of said blocks and arms again mutually engaged, opposite portions of each block, in all adjustments thereof, being engageable by the associated screws so that each block may be held in the desired adjustment relative to the associated arm, each block being exposed for all positions of said block to enable said block to be grasped between the thumb and a finger to facilitate installation, adjustment and removal of each block.

5. In an adjustable hinge, a pintle support comprising arms having substantially aligned holes for receiving a pintle, means for securing said arms to a wall, said arms being spaced apart to accommodate between them the eye of a door hinge strap, said holes being oversize to permit a pintle therein to be adjusted laterally relative to its axis, each arm having corrugations about its hole at the surface thereof remote from said space, set screws carried in association with said arms, and adjusting blocks having pintle-receiving holes substantially smaller than the arm holes and having corrugated surfaces engageable with the corrugated surfaces of the respective arms, said blocks being shiftable free of said arms and transversely to said corrugations and reengageable with said arms at locations removed from the previous locations, with the corrugated portions of said blocks and arms again mutually engaged, opposite portions of each block, in all adjustments thereof, being engageable by the associated screws so that each block may be held in the desired adjustment relative to the associated arm.

5. In an adjustable hinge, a pintle support comprising arms having substantially aligned holes for receiving a pintle, means for securing said arms to a wall, said arms being spaced apart to accommodate between them the eye of a door hinge strap, said holes being oversize to permit a pintle therein to be adjusted laterally relative to its axis, each arm having corrugations about its hole at the surface thereof remote from said space, set screws carried in association with said arms, and adjusting blocks having pintle-receiving holes substantially smaller than the arm holes and having corrugated surfaces engageable with the corrugated surfaces of the respective arms, said blocks being shiftable free of said arms and transversely to said corrugations and reengageable with said arms at locations removed from the previous locations, with the corrugated portions of said blocks and arms again mutually engaged, opposite portions of each block, in all adjustments thereof, being engageable by the associated screws so that each block may be held in the desired adjustment relative to the associated arm, each block being exposed for all positions of said block to enable said block to be grasped between the thumb and a finger to facilitate installation, adjustment and removal of each block.

6. In an adjustable hinge, a pintle support comprising arms having substantially aligned holes for receiving a pintle, means for securing said arms to a wall, said arms being spaced apart to accommodate between them the eye of a door hinge strap, said holes being oversize to permit a pintle therein to be adjusted laterally relative to its axis, each arm having corrugations about its hole at the surface thereof remote from said space, lugs adjacent the ends of the corrugations and projecting away from said space, set screws in said lugs, and adjusting blocks having pintle-receiving holes substantially smaller than the arm holes and having corrugated surfaces engageable with the corrugated surfaces of the respective arms, each block being shorter, in the direction of the corrugations, than the space between the associated lugs, said blocks being shiftable free of said arms and transversely to said corrugations and reengageable with said arms at locations removed from the previous locations, with the corrugated portions of said blocks and arms again mutually engaged, opposite portions of each block, in all adjustments thereof, being engageable by the associated screws so that each block may be held in the desired adjustment relative to the associated arm, and a wall-engaging portion extending from each arm away from said space and united with said lugs for reinforcing said arm.

CLARENCE M. JAHN.
